J. Lombard,
Washing Machine,
Patented Sep. 9, 1835.

Sept 9. 1835

J.

James Lombard of Readfield State of Maine

Letters Patent

The schedule referred to in these Letters Patent and making part of the same, containing a description in the words of the said James Lombard himself of his improvement in a Machine for washing.

To all to whom these presents shall come,
Be it known that I James Lombard of Readfield in the County of Kennebec & State of Maine Physician have invented a new and useful improvement in the machine for washing and that the following is a full and exact description of the construction and operation of said machine as invented or improved by me Reference being had to the accompanying plate. Fig 1. Is a representation of the machine as in action, A. is a tub or cistern upon legs, made of any required size the bottom of this cistern is circular and inside it is covered with a flat or fluted flooring.

This cistern may be covered with a lid if necessary, B. Is an interior cistern or semicylinder suspended within the outer cistern A. having its circumference covered with fluted boards or with fluted rollers as hereafter described. This interior cistern constitutes the rubber and is made with two side pieces over which is bent a board fluted, except the top are put strips of boards to strengthen it. This makes it hollow and renders it convenient to put dirty or other clothes while not undergoing washing or weight may be put in to give power or momentum to it. This rubber (B.) is suspended by a piece of scantling or wooden rod or board D. by a hinge or snipe bill at C. and by a strap chain or string at E. This passes up thro' the end of D. and can be lengthened or shortened at pleasure accordingly as you wish the rubber to prep harder

10.
or left against the bottom of A, the piece D, passes thro a crop piece C, which is placed in the frame work. In by wedges at each end and the piece D, can be pushed backward and forward, thus it ~~can~~ and confined in its place by a pin H. This enables you to suspend the inner cylinder or rubber B, more or less from the centre and modify its pressure and action upon the clothes. On one end of D, is fastened an upright rod G, for the purpose of taking hold when operating the machine or a crutch may be attached to one of the wedges of C, fig. 2, Is a section of the machine having fluted rollers in the rubber, A is the piston, B, the rubber, D the rod to which it is attached C, the hinge, F, the trap. C, the crop piece, this which D, passes G, the handle or lever, fig 3. Is also a section having the Rubber coated up, in order to show its action,

Operation, nothing more is necessary after putting in the requisite quantity of water and clothes, than to apply the hand to the handle, or lever G, & pushes it back and forth,

Claims, I claim the general arrangement of the parts constituting the machine as above described and more particularly,

1. My form and application of the rubber or interior cylinder as above described, 2. my mode of suspending and operating my rubber, as above described being made either with a fluted flaring or with fluted rollers, 3. The application & use of the trap or chain at the end of the rubber, &c, whereby the pressure is regulated & also the rubber allowed to yield or be liberated when clogged or there is too much pressure;

For testifying that the above is a true specification of my said improvement as above described I have hereunto set my hand this 22nd day of July A.D. 1835
